UNITED STATES PATENT OFFICE.

WILLIAM H. MOREHOUSE, OF PASADENA, CALIFORNIA.

LIGHT-RAY REGULATOR.

1,275,074.

Specification of Letters Patent.

Patented Aug. 6, 1918.

Application filed September 24, 1917. Serial No. 192,926.

To all whom it may concern:

Be it known that I, WILLIAM H. MOREHOUSE, a citizen of the United States, residing at Pasadena, in the county of Los Angeles and State of California, have invented new and useful Improvements in Light-Ray Regulators, of which the following is a specification.

This invention relates to a light ray regulator.

It is the principal object of this invention to provide a device which may be readily interposed between the source of light and lens within automobile headlights and which will bend the light rays in a manner to prevent them from producing a glare and at the same time directing them upon the roadway to produce a maximum amount of illumination without materially dimming the light.

Other objects will appear hereinafter.

The invention is illustrated, by way of example, in the accompanying drawings in which:

Figure 1 is a view in vertical section as seen through a headlight and particularly discloses the manner in which the ray regulator is mounted.

Fig. 2 is a view in front elevation illustrating the lamp with its lens removed and the ray regulator in position.

Fig. 3 is a view in perspective illustrating one of the deflecting vanes as viewed from above.

Fig. 4 is a view similar to Fig. 3 illustrating one of the deflecting vanes as viewed from below.

Referring more particularly to the drawings, 10 indicates the outer case of a headlight within which is mounted a parabolic reflector 11. A lens frame 12 is secured over the front of the case and the reflector and supports a lens glass 13. Mounted at the rear of the reflector is an incandescent lamp 14 which is positioned within a socket 15 held by the case 10 and through which it extends. It will be understood that the design of the lamp is not essential to the present invention but that the ray regulator 16 is adapted to be operatively mounted upon headlights of various types.

The ray regulator as here shown is formed of a series of equally-spaced horizontally-disposed deflecting vanes 17 which are su-

perimposed one above the other and are 55 mounted upon rods 18 and 19. These rods extend substantially vertical, being slightly inclined toward each other as they approach a mounting plate 20 at the top of the regulator. This plate has an arcuate outer face 60 which conforms to the lens frame 12 within which it is held. The lower ends of the rods 18 and 19 are secured to the lowermost vane of the regulator. This vane in turn is secured to a lower mounting plate 21 by means 65 of bolts 22 and 23. This lower plate is angular in section and has a front arcuate portion conforming to the frame 12 in the same manner as the plate 20. Brace wires 24 and 25 extend downwardly through openings 26 70 and 27 in each vane. The vanes are so constructed that the metal punched from the perforations 26 and 27 will form tangs 28 which extend downwardly and space the vanes equal distances from each other. The 75 openings 29 at the forward corners of the vanes through which the rods 18 and 19 pass may also be formed with tangs 28 for spacing purposes.

Reference being had to the drawings, it 80 will be seen that the vanes are all of different lengths and that some of them vary as to width as well. The length of the vanes is graduated from the lower vane to the top vane in uniform order. The length of 85 the lower vane is substantially the length of the cord of an arc formed around the bottom of the lens frame 12. The graduation in the lengths of the vanes is directly related to the curved surface of the reflector 11 so 90 that the side rays thrown from the reflector may pass through the lens without obstruction or deflection. It is manifest that these rays will not produce a glare if the headlight is properly set. When considered in plan, 95 each of the vanes has ends which converge rearwardly to further prevent obstruction of the side rays of light. As shown in Fig. 1, the vanes are substantially the same width from the bottom of the regulator to the 100 center line of the headlight. From this point they are gradually reduced in width to permit the light rays from the lamp 14 to pass between them and be diverted downwardly without dimming the light. It will 105 be understood that the vanes of the regulator are not arranged to extend the entire height of the headlight opening but ter-

minate a distance from the top thereof, said distance being determined by the shape of the reflector to allow rays which are not damaging to pass from the reflector without 5 obstruction.

In operation, the ray regulator is mounted within the headlight as particularly shown in Fig. 1 and is held by the lens which is positioned thereover. When the lamp 14 is 10 lighted, its front rays will pass outwardly between the vanes 17 while the remaining rays will fall upon the curved surface of the reflector 11 and will thereafter be projected through the headlight opening. The light 15 rays passing from the headlight along the central portion of the light beam will pass between the vanes of the regulator and will be bent so that the glaring portion of the light beam will be diverted downwardly 20 upon the road and will not be objectionable to pedestrians or other drivers. The vanes may be finished with a dull surface upon 25 their upper and lower faces, but it is preferable to polish the upper face of each vane so that the rays will be more readily reflected along a downward path of travel without glare.

It will thus be seen that the device here disclosed is decidedly simple in its construction, may be easily mounted within headlights of ordinary design, and will act effectively to regulate the beam of light passing from the headlight.

While I have shown the preferred construction of my light ray regulator as now known to me, it will be understood that various changes in the combination, construction and arrangement of parts may be made 35 by those skilled in the art without depart-

ing from the spirit of my invention as 40 claimed.

I claim:

1. The combination with a headlight having a parabolic reflector, a lens in front of the reflector, and a light between the lens 45 and the reflector, of a light ray regulator comprising a series of equally spaced horizontally disposed deflecting vanes mounted one above the other upon vertically extending rods, brace wires extending through the 50 vanes, a lower mounting plate fixed in position behind the lens, bolts securing the lower vane to the lower mounting plate, and an upper mounting plate secured in position behind the lens; the upper ends of the rods 55 being attached to the upper mounting plate.

2. The combination with a headlight having a parabolic reflector, a lens in front of the reflector, and a light between the lens and the reflector, of a lower mounting plate 60 secured in position behind the lower part of the lens, an upper mounting plate secured in position behind the upper part of the lens, rods secured to the upper mounting plate and extending downwardly and diverging, a series of vanes having punched holes; the punchings from the holes being turned to form spacing tangs and there being other holes through which the rods extend, so as to mount the vanes in horizontal 65 positions equally spaced apart; brace wires inserted through the holes from which the tangs are cut to hold the vanes together, and bolts securing the lower vane to the lower mounting plate.

In testimony whereof I have signed my name to this specification.

WILLIAM H. MOREHOUSE.
